MECHANICAL REFRIGERATING APPARATUS

Harry S. Estler, Detroit, Mich., assignor to Chicago Pneumatic Tool Company, New York, N. Y., a corporation of New Jersey

Application December 23, 1929
Serial No. 415,914

17 Claims. (Cl. 62—116)

This invention relates to improved refrigerating apparatus generally but with particular reference to refrigerating outfits of the small capacity type such as those intended for use in the 5 home.

One of the objects of the invention is to provide improved means for the removal of heat by natural draft. Another object is to incorporate the same into an apparatus unit for installation 10 in the machine compartment of a household refrigerator. Other objects will be apparent from the detailed description which follows.

A very large proportion of household type refrigerators are installed in kitchens where the 15 atmosphere is often at a high temperature on account of cooking, ironing and similar operations. The known types of machines having natural draft condensers utilize the air at the middle or upper portions of the kitchen for cooling the 20 condenser, thus imposing an extra load on the mechanism and involving extra expense for operation. Instead of locating the condenser on top of the refrigerator on the back or side where it is surrounded by heated air, the present invention 25 involves the combination with the compressor of a suitable condenser placed below it and close to the floor so as to be surrounded by the coolest air available in the location occupied by the refrigerator. The invention further involves 30 protecting the condenser from heat radiated from the compressor and/or the motor but providing, if desired, for upward movement of air from the condenser to carry away the heat of these parts. The quantity of air permitted to flow over the 35 machine parts of the apparatus, whether or not it first comes in contact with the condenser, may be proportioned in any suitable manner, as by the use of baffles.

In order to illustrate the invention concrete 40 embodiments thereof are shown in the accompanying drawing in which:

Fig. 1 is a vertical sectional view through a household refrigerator cabinet, and

Fig. 2 is a similar view showing a modified arrangement.

In the form shown in Fig. 1 the refrigerator cabinet has a food storage compartment A containing an evaporator 3 of any suitable or desired type for extracting heat therefrom, and beneath 50 the food compartment an apparatus compartment B containing the refrigerating mechanism. This compartment B has mounted therein as a unit the remaining portions of the refrigerating apparatus comprising pump 4, motor 5 for driving the pump and a condenser 6 arranged to be

cooled by the natural draft of air thereover. Compressor 4 has a suction line 7 connected to the top of evaporator 3 and a discharge line 8 connected to condenser 6, the other end of the condenser being connected by a conduit 9 through 60 an expansion valve 10 of any suitable or desired type to evaporator 3 thus completing the refrigerating circuit. Compressor 4 and electric motor 5 may be mounted together in a single casing to form a sealed motor-pump unit. To provide 65 for free movement of air for cooling purposes, compartment B has one or more inlets 11 close to the floor and one or more outlets 12 at the top.

Referring now to the apparatus unit and to the arrangement of the condenser 6 relative 70 thereto, it is to be noted that the condenser has a horizontally disposed part 6a interposed between compressor 4 or motor-pump unit 5, 4 and the floor, also an angularly disposed portion 6b remote from the pump and in the present instance extending substantially vertically at the back of compartment B. Means are provided for protecting the horizontal portion 6a of condenser 6 from the radiant heat of pump 4 and motor 5; such means may be arranged to permit the 75 passage of air from condenser portion 6a to carry away the heat thereof. By preference the means take the form of a perforated plate 13, the upper portion having a bright reflecting surface. The 80 perforations may be effected by punching and striking up portions of plate 13 as indicated. By the provision of a baffle 14 between pump 4 and the angular part 6b of condenser 6, only a portion 85 of the cooling air passing over condenser 6 is permitted to come into contact with motor-pump unit 5, 4 and all heat exchange between 90 compressor 4 and condenser part 6b is prevented.

In the modified form of the invention shown in Fig. 2, both the inlet 11' and the outlet 12' for the cooling air in apparatus compartment 95 B' are at the front of the cabinet. The apparatus unit has its compressor 4' at right angles to the position shown in Fig. 1 and condenser 6' is wholly horizontally disposed beneath the compressor with an apertured reflector member 100 13' interposed to protect the condenser from radiated heat from pump 4' but to permit passing of radiated heat from the condenser. In this instance member 13' does not extend across cabinet 105 B' but only somewhat beyond compressor 4' leaving a large open space toward the back of the compartment for the upward movement of the cooling air. This space is divided into substantially equal parts by a downwardly extending baffle member 14' which has a portion curv- 110

ing over the top of the compressor 4' and dividing outlet 12' into two substantially equal parts. Thus the ascending currents of air which carry away heat from condenser 6' are divided 5 and one portion is kept wholly out of heat-exchange relation with pump 4' by the baffle member 14'. In other respects the elements making up the refrigerating outfit disclosed in Fig. 2 are the same as those in Fig. 1 and have a similar 10 arrangement of connections.

From the above it will be apparent that the arrangement of parts in the present invention is such as to dispose the condenser in the coolest air available. It further prevents the radiation 15 of heat from the compressor or motor-pump unit to the condenser and involve the use of as much or as little of the cooling air for the condenser as is desired to carry away the heat of the compressor or motor-pump unit. Any desired portion 20 of the condenser may be arranged to be wholly out of heat exchange relation with the other parts of the apparatus. With either of the arrangements indicated, the capacity of a given refrigerating apparatus is increased and its operating cost diminished.

While the invention has been herein disclosed in what are now considered to be preferred forms, it is to be understood that the invention is not limited to the specific details thereof but covers 30 all changes, modifications and adaptations within the scope of the appended claims.

I claim as my invention:

1. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment and a condenser having angular portions, one of which extends horizontally beneath said compressor.

2. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, and means interposed between said compressor and said condenser restricting the passage of radiant heat but permitting the passage of convective heat.

3. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, and means maintaining a part of the cooling air passing over said condenser out of contact with said compressor.

4. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a condenser having a part extending horizontally beneath said compressor and an angularly disposed part, and means

80 preventing heat exchange between said compressor and said angular part of said condenser.

5. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, and a reflector member interposed between said compressor and said condenser and providing for passage of convective currents of air from the latter to the former.

6. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, and an apertured reflector interposed between said compressor and said condenser to partially prevent radiant heat 100 from the former from reaching the latter.

7. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, a reflector member interposed between said compressor and said condenser and providing for passage of convective currents of air from the latter to the former, and means maintaining a part of the cooling air passing over said condenser out of contact with said compressor.

8. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, an apertured reflector interposed between said compressor and said condenser to partially prevent radiant heat from the former from reaching the latter, and means maintaining a part of the cooling air passing over said condenser out of contact with said compressor.

9. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a horizontally extending condenser between said compressor and a floor supporting the refrigerator, an apertured reflector interposed between said compressor and said condenser to partially prevent radiant heat from the former from reaching the latter, and a downwardly extending baffle for maintaining a part of the cooling air passing over said condenser out of contact with said compressor.

10. In a household refrigerator having a food storage compartment and an apparatus compartment therebeneath having an air inlet at the bottom and a vent adjacent the top thereof, refrigerating apparatus in said apparatus compartment

- comprising a compressor adjacent the bottom of the compartment, a condenser having a part extending horizontally beneath said compressor and an angularly disposed part, means interposed between said compressor and the horizontal part of said condenser restricting the passage of radiant heat but permitting the passage of convective heat, and means preventing all heat exchange between said compressor and said angular part of 5 said condenser.
10. said condenser.
11. In a household refrigerator having a food storage compartment and an apparatus compartment therebeneath having an air inlet at the bottom and a vent adjacent the top thereof, refrigerating apparatus in said apparatus compartment comprising a compressor adjacent the bottom of the compartment, a condenser having a part extending horizontally beneath said compressor and an angularly disposed part, an apertured reflector 15 interposed between said compressor and the horizontal part of said condenser to partially prevent the passage of radiant heat but to permit the passage of convective heat, and a downwardly extending baffle interposed between said compressor 20 and the angular part of said condenser.
12. An apparatus unit for refrigerating systems comprising a compressor and a horizontally extending condenser secured beneath said compressor and in spaced relation thereto, and means interposed between said compressor and said condenser permitting the passage of convective heat but resisting passage of radiant heat.
13. An apparatus unit for refrigerating systems comprising a compressor, a horizontally extending condenser secured beneath said compressor and in spaced relation thereto, and a deflector having upwardly struck portions interposed between said compressor and said condenser for partially preventing radiant heat from 25

- said condenser from reaching said compressor but permitting convective heat from the former to pass to the latter.
14. An apparatus unit for refrigerating systems comprising a compressor, a horizontally extending condenser secured beneath said compressor and in spaced relation thereto, and baffle means for keeping a part of the cooling air passing over said condenser out of contact with said compressor. 80
- 85
15. Apparatus for refrigerating systems comprising a motor pump unit, a condenser having a part extending horizontally beneath said motor-pump unit and in spaced relation thereto and an angular part remote from said motor-pump unit, and means protecting said condenser parts from the radiant heat of said motor-pump unit. 90
- 95
16. Apparatus for refrigerating systems comprising a motor pump unit, a condenser having a part extending horizontally beneath said motor-pump unit and in spaced relation thereto and an angular part remote from said motor-pump unit, and means protecting said condenser parts from the radiant heat of said motor-pump unit, 100 said means permitting the passage of convective heat from the horizontal part of said condenser to said motor-pump unit.
17. Apparatus for refrigerating systems comprising a motor pump unit, a condenser having a part extending horizontally beneath said motor-pump unit and in spaced relation thereto and an angular part remote from said motor-pump unit, a perforated reflector plate between said motor-pump unit and the horizontal portion of said 110 condenser, and a downwardly extending baffle between said motor-pump unit and the angular portion of said condenser. 105
